UNITED STATES PATENT OFFICE.

WILLIAM GALLIMORE, DECEASED, LATE OF GALAX, VIRGINIA, BY SURILDA P. GALLIMORE, ADMINISTRATRIX, OF GALAX, VIRGINIA, ASSIGNOR OF ONE-THIRD TO DAVID M. BRYANT, OF CLIFFVIEW, VIRGINIA.

SAFETY DEVICE FOR ELEVATORS.

1,246,256.

Specification of Letters Patent. Patented Nov. 13, 1917.

Application filed July 12, 1917. Serial No. 180,181.

To all whom it may concern:

Be it known that WILLIAM GALLIMORE, deceased, late a citizen of the United States, and resident of Galax, in the county of Carroll, State of Virginia, invented new and useful Improvements in Safety Devices for Elevators, and that SURILDA P. GALLIMORE, the duly-constituted administratrix of the estate of WILLIAM GALLIMORE, deceased, 10 does hereby declare the following to be a full, clear, and exact description of the said invention of said decedent, WILLIAM GALLIMORE, and such as will enable others skilled in the art to which it appertains to make 15 and use the same.

The present invention relates to that class of devices intended to prevent elevators from falling in case of breakage of the suspending cable or cables.

20 Numerous devices have heretofore been devised for attaining the same end, but the object of this invention is to provide means which will be comparatively simple and inexpensive, yet highly efficient, and with this 25 general object in view, the invention resides in the novel features of construction and unique combinations of parts to be herein-after fully described and claimed, the descriptive matter being supplemented by the 30 accompanying drawings which form a part of this specification and in which;

Figure 1 is a side elevation with parts broken away and in section, showing the relative positions of parts when all parts of the 35 raising and lowering mechanism are in operative condition;

Fig. 2 is a duplicate of Fig. 1 with the exception that it illustrates the relative position of parts when the elevating cable 40 should break from any cause;

Fig. 3 is a bottom plan view of the elevator; and

Fig. 4 is a detail perspective view of the upper crossed ends of the two levers to 45 which the elevating cables are connected.

In the drawings above briefly described, the numeral 1 designates a common type of elevator, whereas the numeral 2 has reference to the usual vertical tracks between 50 which said elevator slides, the inner side of said tracks being preferably provided with vertically spaced teeth 3, as shown clearly in Figs. 1 and 2. The elevator 1 includes

a platform 4, a pair of standards 5 rising from said platform, and a horizontal crown bar 6 secured at its end to the upper ends of said standards. It is to the bar 6 that the raising and lowering cables 7 are usually connected. Due to the nature of the present invention, however, said bar is provided with a longitudinal slot 8 through which a pair of levers 9 extend, it being to the upper ends of these levers that said cables are attached.

The levers 9 are fulcrumed near their lower ends at 10 to the standards 5, said levers preferably projecting through vertical slots 11 in said standards as shown, and having their lower extremities 12 shaped for anti-slipping engagement with the teeth 3. The two levers converge upwardly and cross each other near their upper ends, said last named ends having enlarged heads 13 formed thereon to which the cables 7 are attached. The heads 13 are of considerably greater thickness than the levers 9 and the lower edges of said heads thus form transverse shoulders 14, the shoulder of each lever abutting the other lever as will be clear from the drawings, in order to maintain 80 said levers in crossed relation. Should the cables 7 be broken, however, a coiled spring 15 serves to draw the two levers toward each other at their upper ends so that their lower ends 12 are thrown outwardly into engagement with the teeth 3, thus preventing the elevator from falling. During this operation, the weight of the heads 13 assists materially in quickly throwing the levers to 85 operative position.

The cables 7 are shown wound around a suitable drum 16 which may either be located at one of the lower floors of the building, or at the top thereof. The former location being illustrated, with the result that 90 pulleys 17 are shown around which said cables are trained. A slack cable 18 is also wound upon the drum 16 and passes around suitable guide pulleys 19, the lower end of said cable being connected to a second locking means which is automatically brought into play to prevent falling of the elevator in case the levers 9 should for any reason fail to operate.

The locking means last referred to, 105 consist of a pair of bolts 20, mounted slidably

beneath the platform 4 and pivoted at their inner ends to the opposite ends of a horizontal lever 21 which is fulcrumed centrally as shown at 22. One end of the cable 18 is 5 connected to one end of lever 21, as shown most clearly in Fig. 3, so that whenever said cable is drawn taut by breakage of the cables 7, it will so operate lever 21 as to throw both bolts 20 outwardly into engagement with the teeth 3. This will prevent any possibility of the elevator dropping by gravity, even though the levers 9 should for any reason fail to operate as intended. A 10 manual control, preferably in the form of a vertical lever 23, is carried by the platform 4, said lever being connected at its lower end by a link or the like 24, with the lever 21. By this means, whenever the elevator is stopped at any floor, and it is 15 intended that it shall remain at this elevation for a considerable length of time, the operator need only actuate the lever 23, thus projecting both bolts 20 into adjacent teeth 3 so that it is impossible for the elevator to 20 be lowered.

In operation, assuming that all parts are 25 properly operating, the drum 16 is rotated to either raise or lower the elevator 1, as occasion may demand, the entire weight of said elevator being supported on the cables 7 and the crossed levers 9, the cable 18 now remaining slack so that it exerts no tendency to operate the bolts 20. Should the cables 7 become broken or damaged, however, so that they no longer effectively support the weight of the elevator, the cable 18 is drawn taut, with the result that the lower end of this cable pulls upon lever 21 and so actuates the latter as to project both bolts 30 20. At substantially the same time, since the levers 9 are released by the defective cables 7, said levers will be rocked around their fulcrums 10 until their lower extremities 12 are brought into engagement with 35 the teeth 3. Two locking means are thus applied simultaneously to prevent any possibility of the elevator falling. It will be understood, however, that although both means are shown on an elevator and are 40 45

preferably employed together, either locking means could well be installed without the other, and would be very effective.

From the foregoing, taken in connection with the accompanying drawings, it will be obvious that although the invention is of comparatively simple and inexpensive nature, it will be highly efficient and durable for the purposes intended. Since probably the best results are obtained by the specific construction shown and described, such construction constitutes the preferred form of the improved safety appliance. It is to be understood, however, that within the scope of the invention as claimed, numerous minor changes may be made without sacrificing the principal advantages.

I claim:

The combination of an elevator including a platform, a pair of vertical standards rising from said platform and having vertical 70 slots, a crown bar extending between the upper ends of said standards and secured thereto, said crown bar having a longitudinal slot, vertical tracks between which said elevator slides, said tracks having teeth 75 on their inner sides, a pair of crossed levers extending through the slots of said standards and crown bar and fulcrumed to the former, the lower ends of said levers being shaped for engagement with said teeth, 80 heads on the upper ends of said levers, said heads being of greater thickness than said levers and extending laterally therefrom to form shoulders, the shoulder of each lever abutting the other lever to maintain them 85 in crossed relation, and raising and lowering means for the elevator connected to said heads.

In testimony whereof I, SURILDA P. GALLIMORE, administratrix of the estate of WILLIAM GALLIMORE, have hereunto set my hand in the presence of two subscribing witnesses.

SURILDA P. GALLIMORE,
Administratrix of said William Gallimore,
deceased.
